US0D1074733S

(12) **United States Design Patent** (10) Patent No.: **US D1,074,733 S**
 Knight et al. (45) Date of Patent: ** May 13, 2025

(54) DISPLAY SCREEN WITH GRAPHICAL USER INTERFACE OF A GAMING MACHINE	5,951,397 A	9/1999	Dickinson
(71) Applicant: LNW Gaming, Inc. , Las Vegas, NV (US)	6,027,115 A	2/2000	Griswold et al.
(72) Inventors: Jamie Knight , Henderson, NV (US); George Bouvier , Henderson, NV (US); Richard Milosevich , Las Vegas, NV (US); Kenneth Shawn Soong , Henderson, NV (US)	6,056,642 A	5/2000	Bennett
(73) Assignee: LNW Gaming, Inc. , Las Vegas, NV (US)	6,089,977 A	7/2000	Bennett
(**) Term: 15 Years	6,224,482 B1	5/2001	Bennett
(21) Appl. No.: 29/871,836	6,251,013 B1	6/2001	Bennett
(22) Filed: Feb. 28, 2023	6,270,411 B1	8/2001	Gura et al.

CLAIM

The ornamental design for a display screen with graphical user interface of a gaming machine as shown and described.

DESCRIPTION

The FIGURE is a front view of a display screen with graphical user interface of a gaming machine showing our new design.
 The broken line showing of a display screen with graphical user interface of a gaming machine is included for the purpose of showing portions of the article that form no part of the claimed design.

FIGURE
